Primary Examiner — Mojtaba Tehrani(57) **CLAIM**

The ornamental design for an adjustable liner for a refrigerator drawer, as shown and described.

DESCRIPTION

FIG. 1: is a front perspective view of the adjustable liner for a refrigerator drawer, showing my new design;

FIG. 2: is a side elevational view thereof;

FIG. 3: is a front elevational view thereof;

FIG. 4: is a rear elevational view thereof;

FIG. 5: is a top plan elevational view thereof;

FIG. 6: is a bottom plan view thereof;

FIG. 7: is a cross section view taken along the line shown in FIG. 5; and,

FIG. 8: is a top perspective view thereof, in an alternate state.

The evenly broken lines in the drawings disclose the unclaimed portion of the adjustable liner for refrigerator drawer; the dash dot broken lines in the drawings disclose unclaimed cross sectional cut line shown in FIG. 5; The broken lines for no part of the claim design.
